UNITED STATES PATENT OFFICE.

DAVID HARRIS, OF STAR, WISCONSIN.

ENVELOP.

SPECIFICATION forming part of Letters Patent No. 594,620, dated November 30, 1897.

Application filed February 1, 1897. Serial No. 621,488. (No model.)

To all whom it may concern:

Be it known that I, DAVID HARRIS, a citizen of the United States, residing at Star, in the county of Vernon and State of Wisconsin, have invented a new and useful Envelop, of which the following is a specification.

My invention relates to envelopes particularly adapted for first-class mail-matter and also designed for express and other packages; and the object in view is to provide an envelop wherein the exposed flaps, including the closing-flap, are interlocked and are sealed at such points as to be inaccessible without mutilation of the receptacle.

15 A further object of the invention is to provide an envelop having a closing-flap which is secured in place by means of gummed surfaces of the minimum extent, whereby the facility of closing the receptacle is increased. 20 A further object of the invention is to provide an envelop having a reinforced back, of which the members are locked in their normal positions by means of both the closing and the bottom flaps, whereby said members 25 are secured at intermediate points by the same gummed surfaces which serve to secure the closing and bottom flaps in place.

20 A further object of the invention is to provide an envelop having interlocked members, 30 wherein reduced tongues are dispensed with to reduce the cost of manufacture and the liability of detachment of such tongues.

Further objects and advantages of this invention will appear in the following description, and the novel features thereof will be particularly pointed out in the appended 35 claims.

In the drawings, Figure 1 is a plan view of a blank from which the envelop embodying 40 my invention is formed. Fig. 2 is a rear view of the envelop with the closing-flap in its open position as seen before the introduction of mail or other matter. Fig. 3 is a similar view showing the closing-flap in its operative or 45 sealed position. Fig. 4 is a longitudinal section of the closed envelop on the line $\alpha\alpha$ of Fig. 3.

Similar numerals of reference indicate corresponding parts in all the figures of the drawings.

50 The envelop-blank embodying my invention consists, essentially, of a main or front

fold 1, integral interior and exterior back folds 2 and 3, attached to the side edges of the main or front fold, and integral end or 55 closing and bottom flaps 5 and 6, attached to the upper and lower end edges of the main or front fold. Each of the back folds 2 and 3 is approximately coextensive with the front fold 1, the exterior back fold 3 being slightly 60 cut away at its outer edge, as shown at 4, to prevent the projection of said edge beyond the contiguous edge of the front fold when the parts are in their normal positions. (Illustrated in Figs. 2 and 3.)

65 The interior back fold 2 is the first to be folded over the front fold in the manufacture of the envelop, after which the exterior back fold 3 is turned over the interior fold and is secured to the latter by a gummed line 10, arranged parallel with the several edges of the exterior back fold.

70 The end flaps 5 and 6 are of less length than one-half the main fold and are preferably semicircular in construction, whereby the 75 length of each is approximately equal to one-half the width of the main fold, and as I desire to provide an interlocking connection between the end flaps and the back folds I preferably slit the exterior back fold at 7, re- 80 spectively, contiguous to the inner edges of the end flaps to form pockets into which the central portions of the edges of the end flaps are inserted, as shown clearly in Fig. 3, and in order to increase the area of the inclosed 85 portion of each end flap I make the slit 7 of curved construction, bowed outwardly toward the ends of the back fold 3 to form segment-shaped tongues 8. These tongues are

90 gummed upon their inner surfaces or those surfaces contiguous to the interior back fold to adhere to the exterior surfaces of the flaps 5 and 6, while the flaps are gummed upon their inner surfaces, as shown by the dotted lines 9, to adhere at their centers to the exterior 95 surface of the interior back fold 2 and at their side portions to the outer surface of the exterior back fold 3. Thus each end flap, in addition to being centrally fitted in a pocket in the exterior back fold, is gummed at a central point to the interior back fold and at opposite sides of said central portion to the exterior back fold, while the segmental tongue under which the central portion of the flap is

extended is gummed to the exterior surface of said flap. Hence the central portion of each flap serves to connect the exterior and interior back folds at an intermediate point, 5 the point of attachment of said flap to the interior back fold being inaccessible by reason of the protection afforded by the overlapping segmental tongue.

Obviously one of the end flaps—namely, the 10 closing-flap 5—is left open or unsecured, as shown in Fig. 2, when the envelop embodying my invention is placed upon the market, the bottom flap 6, however, being secured, as above described and as shown in Figs. 2 and 3, to 15 insure the holding of the members of the envelop in their proper relative positions. After the insertion of the mail-matter or desired contents of the envelop the closing-flap is folded downwardly and secured in the manner hereinbefore explained.

Inasmuch as the closing-flap is of a width equal only to the end edge of the main or front fold (the mail-matter being inserted at the end of the envelop instead of at the side, as in 25 the ordinary practice) a comparatively small extent of gummed surface must be moistened in order to secure the flap in its closed position. After the flap has been inserted centrally into the pocket and properly gummed 30 to the exterior and interior back folds the inner surface of the segmental tongue should be moistened and caused to adhere to the exterior surface of the flap.

Even should the tongue 8 be loosened by 35 means of steam or other agency in the operation of fraudulently opening the envelop, and even should the portion of the flap which adheres to the surface of the exterior back fold be loosened in a similar manner, it 40 will be seen that the inclosed central portion of the flap, which is arranged below the plane of a straight line connecting the extremities of the curved slit 7, will be protected by the exterior back fold, and hence 45 will be practically inaccessible by the means employed for opening envelops. In other words, there will be two thicknesses of material between the exterior surface of the envelop and the adhesive material by which 50 the central portion of the flap is secured to the surface of the interior back fold.

Having described my invention, what I claim is—

1. An envelop having a blank comprising 55 a rectangular front fold, interior and exterior back folds integral with the side edges of the front fold, the exterior back fold being provided at intermediate points with transverse

slits and having its inner surface gummed parallel with its edges to adhere to the outer 60 surface of the interior back fold, and closing and bottom flaps integral with the end edges of the front fold, and of a length greater than the intervals between the extremities of the front fold and said slits, for terminal insertion through the latter, said flaps having 65 gummed inner surfaces to adhere to the outer surfaces of the exterior and interior back folds, and the exterior back fold being gummed contiguous to its slits for adhesion 70 to the exterior surfaces of the flaps, substantially as specified.

2. An envelop having a blank comprising a rectangular main fold, integral approximately coextensive interior and exterior 75 back folds arranged at the side edges of the front fold, the exterior back fold being provided at intermediate points with transverse curved slits, bowed respectively toward the contiguous ends of said fold to form outwardly-extending segmental tongues, and closing and bottom flaps integral with the front fold at its end edges, and of a length greater than the interval between each end edge of the front fold and the contiguous 80 curved slit of the exterior back fold, and adapted to be inserted respectively through said slits, the exterior and interior back folds being adhesively connected at their edges, the flaps and tongue being gummed on their 85 inner surfaces, substantially as specified.

3. An envelop having a blank provided with approximately coextensive front, and exterior and interior back, folds adapted to lie in parallel planes, the said back folds being adhesively connected, and the exterior back fold being slitted to expose the outer 90 surface of the interior back fold; and peripherally-rounded end flaps integral with the end edges of the front fold and adhesively 100 secured, centrally, to the outer surface of the interior back fold and, upon opposite sides of said central points, to the outer surface of the exterior back fold, said exterior back fold being further provided with tongues 105 overlapping and adhesively secured to the exterior surfaces of the end flaps, substantially as specified.

In testimony that I claim the foregoing as my own I have hereto affixed my signature in 110 the presence of two witnesses.

DAVID HARRIS.
